UNITED STATES PATENT OFFICE.

JOHN J. CUNNINGHAM, OF MANCHESTER, NEW HAMPSHIRE.

COVERED METAL ROLL.

1,381,286.

Specification of Letters Patent. Patented June 14, 1921.

Application filed July 3, 1920. Serial No. 894,765.

To all whom it may concern:

Be it known that I, JOHN J. CUNNINGHAM, a citizen of the United States, resident of Manchester, county of Hillsborough, 5 State of New Hampshire, have invented an Improvement in Covered Metal Rolls, of which the following description, in connection with the accompanying drawing, is a specification, like characters on the drawing 10 representing like parts.

This invention relates to covered metal rolls. Such metal rolls covered with a covering layer of leather or other non-metallic material are commonly used in spinning and 15 textile machinery, but are useful for many other purposes. Difficulty is encountered in permanently securing the covering layer to the periphery of the metal roll. When a cementing agent, such as glue, is employed 20 to fasten the covering layer to the metal periphery of the roll and when the roll is subjected to a rubbing or rolling action the cementing agent often becomes crystallized and the bond very easily breaks allowing the 25 covering material to separate from the metal.

The object of this invention is to provide a roll in which the covering layer shall be 30 securely fastened to the metal roll periphery so as to prevent lifting or creeping of the covering layer.

With the foregoing general object in view the invention resides in the novel feature hereinafter fully described and claimed, the 35 descriptive matter being supplemented by the accompanying drawings which form a part of the specification and in which—

Figure 1 is a side elevation of a roll embodying a preferred form of the invention.

Fig. 2 is a diametrical section taken on the line 2—2 of Fig. 1.

Fig. 3 is a detail in transverse section showing the position of the ends of the binding wire ready for fastening.

Fig. 4 is a detail similar to Fig. 3 showing the binding wire fastening in position.

Fig. 5 is a detail of Fig. 3 showing the ends of the binding wire twisted together.

Fig. 6 is a detail in axial cross section 50 taken on the line 6—6 of Fig. 1.

Fig. 7 is a plan view of a roll showing another modification of the invention.

The metal roll itself may be of any suitable size and form. In the construction 55 illustrated a roll suitable for use on a spinning frame is shown and comprises the hub

1 the web or spider 2 and the flange 3 having the flat exterior periphery 4.

The covering layer 5 may be of leather or other suitable non-metallic material and the 60 main object of the invention is to fasten this covering layer 5 securely to the periphery 4 of the metal roll so that the covering layer will not lift or creep when the roll is in use.

In rolls used in the textile art this covering 65 layer 5 is generally used as a foundation for an outer covering layer 6 of very fine and high grade leather. This outer covering layer 6 takes the wear and has to be replaced from time to time. It can be cemented sat- 70 isfactorily to the inner covering layer. But difficulty is encountered in cementing or se- 75 curing the main or inner covering layer 5 to the metal periphery of the roll. The pres- ent invention affords a means by which this difficulty is eliminated.

In the present invention a wire binder is employed encircling the covering material. There may be one or more of these wire binders as desired or the wire binder may be 80 in the form of a continuous helix as illus- 85 trated in Fig. 7. The wire binder is placed under tension before it is secured in position and will embed itself into the surface of a covering layer or if desired the covering layer may first be grooved as at 8 to receive the wire binder and thus insure an even outer peripheral surface on the inner cov- 90 ering layer 5 to receive the outer covering layer 6.

The inner covering layer is placed in position on the periphery of the metal roll and may first be cemented or glued thereto if desired. The wire binder 7 is then placed about the outer covering layer and in the 95 groove therein if a groove is employed. This wire binder is then brought under a considerable tension so as to firmly clamp the covering layer 5 against the roll periphery and the wire binder is then secured 100 in position. Various means may be em- 105 ployed for securing the wire binder under tension in position and preferably this is done by securing the ends of the wire binder to the metal roll. In the construction illus- 110 trated in Figs. 1, 2, 3 and 4 the ends 9 of the wire binder are passed through a radial hole in the covering layer 5 and the flange 3 on the roll. These ends are then pulled inwardly so as to bring the wire 115 under the heavy tension. A tapered metal pin 10 shown in Fig. 4 is then driven in

place thus locking the ends of the wire to the metal roll and holding the wire binder under tension.

As shown in Fig. 5 the ends 9 of the wire binder 7 may after the wire binder has been brought under tension be twisted together and then a tapered pin driven in to lock the twisted ends to the metal roll, in the same manner as shown in Fig. 4.

It may also be desirable especially in rolls of the larger sizes to secure the wire binder of the metal roll at a point or points intermediate of its ends and thus doubly insure the prevention of lifting or creeping of the covering layer. Such a construction is indicated in Figs. 1 and 6 where at a point diametrically opposite to that at which the ends of the binder wire are secured in place a second securing of the binder wire to the metal roll is effected. At this point a wire staple 11 is passed over the binder wire 7 and driven into a hole 12 extending radially through the covering layer 5 and the flange 3. A tapered metal pin 13 is then driven in alongside of the staple thus firmly locking the staple and consequently the binder wire to the metal roll at this point.

As many binder wires encircling the roll may be employed as desired and in Figs. 2 and 6 two such binder wires are shown. It is already pointed out the binder wire may also be in the form of a continuous helix of any desired pitch and such a construction is illustrated in Fig. 7 where the binder wire 14 is shown as extending in a continuous helix about the periphery of a wide roll 15. In this case the ends of the binder wire 16 are passed through radial holes in the covering layer and metal roll, the wire is brought under heavy tension and tapered pins 17 driven into the holes secur-

ing the ends of the wire to the metal roll. In addition at a plurality of points along the helix a fastening means 18 of the form illustrated in Fig. 6 may be employed to fasten the binder wire at these points securely to the metal roll.

The finishing or outer covering layer 6 may then be secured in place by cementing it in the usual manner to the covering layer 5.

It is obvious that the construction and method of application of this invention may be varied to meet different conditions and requirements.

Having thus described my invention what I claim as new and desire to secure by Letters Patent is—

1. The combination of a metal roll, a covering layer for the roll periphery, and a wire binder encircling the covering layer and fastened under tension at its ends and at a point or points intermediate of its ends to the roll whereby the covering layer is securely held against the roll periphery and lifting or creeping of the covering layer is prevented.

2. The combination of a metal roll, a covering layer for the roll periphery, the said roll and covering layer having an aligned hole extending generally radially therethrough, a wire binder encircling the covering layer and having its ends drawn into said hole under tension, and a tapered pin driven into the hole and locking the ends of the binder wire therein whereby the covering layer is securely held against the roll periphery and lifting or creeping of the covering layer is prevented.

In testimony whereof, I have signed my name to this specification.

JOHN J. CUNNINGHAM.
